UNITED STATES PATENT OFFICE.

DANIEL BRUHN, OF HOBART, INDIANA.

STEEL INTERIOR FOR HOUSES.

Application filed March 21, 1924, Serial No. 700,762. Renewed March 5, 1927.

This invention relates more particularly to an interior steel construction for homes, garages, barns and the like, whereby a sanitary and fireproof structure is adapted to be easily erected without the use of lath, plaster and studding thereby materially reducing the cost of building.

It is an object of this invention to produce a steel interior for houses and the like, wherein a steel framework is provided on which sheet steel walls and ceilings are secured affording a steel interior having a circulating air space between the walls. Said steel interior is fireproof and practically indestructible and is not subject to damage or cracking as is the case when plaster walls are used.

It is also an object to provide an interior steel construction for houses and the like, said steel construction affording flat smooth walls and ceilings which may be papered, painted or otherwise decorated in any desired manner.

Another object of the invention is to provide a steel frame work and steel interior walls and ceilings for a building which may be constructed at a less cost than a similar building built under the old methods, since the use of studding, lathing, plastering are eliminated and since the time of erection is comparatively short as the materials for the framework and interior is all fabricated at the factory and shipped ready to be assembled.

It is a further object of the invention to provide a steel interior for buildings wherein the interior trim may be put on and the doors, and window frames put in place at the same time that the outside or veneer walls are being constructed.

It is furthermore an object of the invention to provide a steel interior for buildings whereby the interior decorating may be done at once or as soon as the interior wood work is finished, without waiting for plaster to dry or season.

It is an important object of this invention to provide a steel construction for homes and the like wherein the interior walls and ceiling are of sheet steel which may be readily and easily secured in position to form the interior of the building and wherein no waiting is necessary before the exposed surfaces of the interior walls may be decorated.

Other and further important objects of

this invention will be apparent from the disclosures in the drawings and specification.

The invention (in a preferred form) is illustrated on the drawings and hereinafter more fully described.

On the drawings:

Figure 1 is a top plan view of a house, with the roof members omitted, and embodying the principles of this invention.

Figure 2 is a sectional view taken on line 2-2 of Figure 1.

Figure 3 is an enlarged fragmentary detail section taken on line 3-3 of Figure 2.

Figure 4 is an enlarged vertical section through a window frame taken on line 4-4 of Figure 1.

Figure 5 is an enlarged fragmentary detail section taken on line 5-5 of Figure 2.

Figure 6 is an enlarged fragmentary detail section taken on line 6-6 of Figure 1 showing parts of an upper story structure.

Figure 7 is a view taken on line 7-7 of Figure 6.

Figure 8 is a view taken on line 8-8 of Figure 2 with the sheet steel walls omitted.

As shown on the drawings:

The reference numeral 1 indicates a floor which may be made of any desired material and upon which the metal base plates 2 of a plurality of metal supporting pillars or pipe posts 3 are rigidly secured. The posts 3 are located in selected positions to be at the intersecting lines of the walls and of course are located depending upon the layout of the house to be constructed. A top plate is integrally formed or rigidly secured on the upper end of each post 3. The top plates are of different shape depending upon whether the posts are located at the juncture of two, three or four walls. The top plates may be straight connecting plates for straight wall extensions, angle plates 4, T plates or cross plates

5 or of any other desired shape that may be necessary.

Secured to the respective top plates by bolts 6 or other suitable means are a plurality of upturned metal channel bars 7. The interior of the house is formed by means of a plurality of sheet steel plates or panels 8 the upper margin of each of which is bent over to afford a hook flange 9. Also integrally formed along the longitudinal edges of each plate 8 are apertured flanges 10 to which the flanges of an adjacent plate 11 are adapted to be bolted. At the corners of a room or at angle portions there are pro-

vided wall plates 11 (Figure 3) bent at an angle at 12 to fit the corner and having a second right angle bend to form a longitudinal flange 13. The flanges 13 are adapted 5 to lie flat against the flanges 10 and are secured thereto by bolts 14 or similar means. The plate flanges 10 and 13 are disposed at right angles to the wall plates and extend across the wall spaces as illustrated in Figure 3. The upper margins of the angle wall plates 11-12 are bent over to afford flange hooks adapted to be hung over the flanges of the channel bar 7.

The lower apertured ends of the sheet 15 steel wall plates 8, 11 and 12 extend downwardly to the floor 1 and are nailed against the sides of wooden floor beams 13 which rest upon the post base plates 2 as shown in Figures 2 and 6.

20 Seated in the channel bars 7 are wooden beams 15 which project slightly above the flanges of the channel bars 7 (Figure 6). Supported on the ceiling beams 15 and secured thereto are a plurality of adjacently 25 disposed sheet steel ceiling plates 16. The floor 1 of the upper story or attic as the case may be is laid upon the ceiling plates as illustrated in Figure 6.

To close the space between the ceiling 30 plates 16 and the upper ends of the wall plates a wooden finishing moulding 17 is nailed to the beams 15 (Figure 6).

Where required door wall plates 18 are put in place and are formed and mounted 35 similar to the other wall plates. Each door wall plate is cut out to afford a suitable opening of a selected height. The wall plates 18 on opposite sides of a wall have flanges 19 formed thereon which are bolted 40 together (Figure 5) and form a door opening wherein a door casing 20 is fitted. Interior trim boards 21 are secured to the door casing and project over the wall plates 18. A door 22 is hung in each door casing where 45 required.

Where windows are to be located sheet steel wall plates 23 are provided and are constructed with upper hook flanges 9 and side flanges 10 similar to the wall plates 8. 50 Each window wall plate is, however, formed with an opening within which a window casing 24 is mounted. Each window casing 24 is secured by nails to wooden strips 25 secured to the outer surfaces of the wall plates 23 (Figure 4). Trim boards 26 are provided around the window casings on the inner side of the window wall plates 23.

After the interior steel construction is erected as described the outside or veneer 60 walls may be laid or built and the roof built in place. The interior decorating may be done as soon as the interior work or trim is finished since there is no plaster to put on and dry before the decorating can be 65 done as in the old building methods.

It will be noted that a steel interior is provided for houses and the like which may be easily assembled from standard steel and wooden pieces so that a house may be constructed in a comparatively short length of 70 time. The walls and ceilings are of sheet steel firmly reinforced by beams and by the connecting flanges which span the air spaces provided between the walls.

The inner exposed surfaces of the metal 75 wall plates and ceiling plates may be painted, papered or decorated in any desired manner immediately after the interior steel work is properly assembled. No drying out of the houses is required as in the case of 80 plaster finished structures.

I am aware that numerous details of structure may be varied through a wide 85 range without departing from the principles of this invention and I therefore do not purpose limiting the patent granted hereon otherwise than necessitated by the prior art.

I claim as my invention:—

1. A steel interior for houses comprising 90 a plurality of supporting pillars, base plates and top plates on the ends of said pillars, channel members secured to said top plates and spanning the distances between said pillars, sheet steel wall plates, hook flanges 95 formed thereon to hook over the flanges of the channel members, longitudinal flanges formed on said wall plates with the flanges of one wall plate disposed adjacent those of another wall plate and secured thereto, wooden ceiling beams seated in the channel members, adapted for supporting a ceiling.

2. A steel interior for houses comprising 100 a plurality of supporting pillars having base plates and top plates on the ends thereof, channel members secured to the pillar top plates, sheet steel wall plates formed to be hung from said channel members and secured to one another, wooden members supported on the pillar base plates and to 105 which the wall plates are secured, wooden beams seated in the channel members, adapted for supporting a ceiling.

3. A steel interior for houses comprising 110 supporting pillars having base plates and top plates formed thereon, wooden members supported on the base plates, channel members supported on the top plates, sheet steel wall plates having the lower ends secured to 115 said wooden members, hook flanges formed on the upper ends of the wall plates and hung over the flanges of the channel members, longitudinal flanges formed on said wall plates and secured to the flanges of adjacent wall plates, in said channel members, adapted for supporting a ceiling thereon.

4. An interior for houses comprising a 120 flooring, uprights secured thereon, channel members supported on said uprights, and 125

hooked wall plates suspended from said channel members to form walls.

5. A steel interior for houses comprising a floor, uprights secured thereon, channel members supported on said uprights and connecting the same, sheet steel wall plates, and hooks formed thereon adapted to engage over the channel members to hold the wall plates suspended in position to form

10 walls.

6. A steel interior for houses comprising a floor, metal posts secured thereon, wooden beams on the floor extending from post to post, metal channel bars supported on the 15 tops of said posts, a plurality of metal wall plates, hooks formed thereon adapted to engage over the channel bars to hold the wall plates suspended in position with the lower ends of said wall plates secured to

20 said wooden beams.

7. A steel interior comprising a plurality of supports, flanged members supported thereon and connecting the supports, and a plurality of wall plates suspended from 25 the flanged members to form walls, each wall plate having a hook flange formed on one end thereof and longitudinal flanges formed on the side margins thereof.

8. A steel interior comprising a floor, holding 30 metal uprights, base flanges formed

thereon secured to the floor, top flanges formed on said uprights, wooden beams on said base flanges, a plurality of plain sheet metal wall plates having the lower ends secured to said wooden beams, hooks formed 35 on the upper ends of said wall plates, channel members supported on said top flanges and engaged by said hooks to hold the wall plates suspended in position, and flanges formed on said wall plates with the 40 flanges of adjacent plates secured to one another.

9. A metal interior comprising supports, flanged members thereon, metal wall plates suspended from the flanged members to 45 form walls having air spaces therein, and means on said wall plates for securing the wall plates one to the other.

10. A metal interior comprising supports, plates of different configuration on said 50 supports, channel members secured to said plates and connecting the supports, said channel members being adapted to support the ceiling, and flanged metal wall plates suspended from the channel members and 55 connected to one another to form the walls of the interior.

In testimony whereof I have hereunto subscribed my name.

DANIEL BRUHN.
